UNITED STATES PATENT OFFICE.

ADDISON V. SANFORD, OF ELMIRA, NEW YORK, ASSIGNOR TO THE DRAKE ACETYLENE GENERATOR COMPANY, OF CORNING, NEW YORK.

ACETYLENE-GAS GENERATOR.

SPECIFICATION forming part of Letters Patent No. 637,165, dated November 14, 1899.

Application filed February 16, 1899. Serial No. 705,680. (No model.)

To all whom it may concern:

Be it known that I, ADDISON V. SANFORD, a citizen of the United States, and a resident of Elmira, in the county of Chemung and State 5 of New York, have invented certain new and useful Improvements in Acetylene-Gas Generators, of which the following is a specification.

My invention relates to that type of acetylene-gas generators wherein the calcium carbid is supplied to the machine in suitable charges which are automatically delivered into water in a generating-chamber at periods determined by the condition of the supply 15 of gas in the gasometer or other distributing means.

My present invention relates more especially to the construction of the generator *per se*; and it consists in certain novel features of construction whereby the generator is improved not only as to its effectiveness in use, but as to convenience in manipulation, cleansing, &c.

My invention will be fully understood upon 25 reference to the accompanying drawings, in which—

Figure 1 is an elevation showing a complete machine to which my present improvements are applied. Fig. 2 is a vertical axial section 30 of the generator. Fig. 3 is a plan of the mechanism which carries and delivers the charges of carbid successively into the generator. Fig. 4 is a horizontal section on the line 4 4 of Fig. 2. Fig. 5 is a vertical axial section through the lower portion of the generator, taken in a plane at right angles to the plane of the section of Fig. 2. Figs. 6 and 7 are respectively an end and a sectional view of the automatically-closing carbid-trap. Fig. 40 8 is a vertical sectional view, on an enlarged scale, of the safety-valve.

Referring to Fig. 1, 1 represents the generator, which is connected by a pipe 2 with a purifier 3, which in turn discharges through 45 a pipe 4 into the gasometer 5. The generator is surmounted by carbid carrying and delivering mechanism, to be hereinafter described, which is mounted upon a vertical shaft 6, which has turning connection through 50 bevel-gears 8 with a shaft 9. The shaft 9 is rotated periodically through the medium of

a catch 10, the lever 11 of which is connected by flexible cord 12 to the bell 13 of the gasometer. The cord 12 passes over pulleys 14 and 15, and the parts are so adjusted that 55 during the settling of the bell the lever 11 is being moved and the shaft 9 and the parts driven by it are rotated, and when the bell reaches the lower limit of its movement the carrying and delivering mechanism will discharge one charge of the carbid into the generator and produce a new supply of gas. By having the work of rotating the shaft 9 constantly imposed on the bell 13 pressure on the gas distributed by the bell is uniform, 65 and fluctuation of the lights resulting from suddenly imposing such work upon the bell as it nears its lower limit is thus avoided. The bell is further provided with a cord 16, which connects with the lever 17 of the safety- 70 valve 18, located in an offset 19 of the pipe 4. Should the bell pass the upper limit of its movement, the lever 17 will be rocked upon its fulcrum and the valve 18 opened, so that surplus of gas may escape into a discharge- 75 pipe 20, commonly used in machines of this character.

The construction of the safety-valve 18 will best be understood upon reference to Fig. 8, where it will be seen that the valve 21 sets 80 with the pressure of the gas in the pipe 19 and not against it. The valve is held normally closed by a spring 22, surrounding its stem 23; but said stem is depressed by the lever 17 through the medium of its forked end 85 24 engaging the neck on the upper end of the valve-rod.

The purifier 3 is preferably constructed, as shown in Fig. 1, with a cylindrical body 25, of any suitable sheet-metal construction, and 90 the cast heads 26, which are held to the cylindrical body by means of the tie-rods 27. Such a construction saves much expense in the purifier and permits it to be readily taken apart for cleansing when occasion requires. 95 A cock 28 may be opened to determine the level of the water contained in the purifier, and a cock 29 is provided for draining the same. 30 represents a cock which may be employed for allowing the escape of air or 100 gas from the purifier when setting up the machine.

Referring to Figs. 2 and 3, it will be seen that the shaft 6 is provided with a spider 31, the arms of which have slotted outer ends 32, which receive the T-heads 33 of the removable carbid-holders 34. The carbid-holders 34 are removable from the machine for charging and are provided with hermetic closures 35, which are held normally closed by means of the latches 36, whose depending arms 37 engage a trip 38, projecting into the path of the arms for releasing the latches as the holders are brought successively over the carbid-trap 39 by rotation of the spider. I do not herein claim, broadly, the removable carbid-holders, or such holders provided with the automatically-opening closures, nor such a holder mounted upon a rotating spider, as these features form the subject-matter of an application filed by me on the 30th day of November, 1898, Serial No. 697,862. I have, however, improved some of the details of construction of these parts and shall claim the same in my present application—that is to say, the slotted spider-arms, with the T-heads, for securing the holders in place are found to be more convenient than the means previously described for the same purpose. I also prefer to incline the tripping-arms 37 rearward with respect to the direction in which the holders travel, as by so doing I am enabled to locate the trip 38, as shown in Fig. 3, in rear of the dumping-point, and thus avoid obstructing the passage of the carbid or causing the carbid to scatter in small particles about the trap 39. I also prefer to support the carbid holding and delivering mechanism from the head 40 of the machine by means of the hangers 41, the lower ends of which enter the slotted ends of the arms 42 of the lower supporting-frame 43 and are there secured by nuts 44. The frame 43 is likewise provided with a step 45 for the shaft 47 and is surmounted by the horizontal diaphragm 46, which divides the upper end of the generator into the carbid-chamber A and the waste-chamber B and likewise provides a support for the trap 39 and trip 38. The trip 38 is mounted, in substantially the manner described in my previous application, upon a shaft 47, turning in bearings 47^a, so that the trip may be turned down out of the path of the releasing-arm 37 when it is desired to remove or replace the holders. The side wall 48 of the generator is preferably made to extend from bottom to top, and thus inclose the entire generator, a door 49 being provided in the upper end of sufficient dimensions to give free access to the carbid-holders for removing or replacing them, while keeping the carbid-chamber normally closed to prevent the escape of odors from the carbid.

The construction of the trap 39 will be understood upon reference to Figs. 6 and 7. It is provided with a supporting-flange 50, which rests upon the diaphragm 46 and has the tapering end walls 51, providing a chute against which the spring-doors 52 are held by a spring

53 in order to keep the chute normally closed, but to permit it to open under the weight of the carbid, which is discharged into the trap. 70

The generating-chamber is represented at C and is formed by a hood 54, which is inserted in the generator so as to be readily removable therefrom. It rests upon a ledge 55, and its edge is protected against the escape 75 of gas by means of the upwardly and inwardly inclined deflector 56. The base of the hood 54 covers the entire horizontal area of the generator; but to give space for the location of a chute by which the carbid is delivered to the generating-chamber the hood is inclined laterally and upwardly to the top of the generating-chamber, so as to present an inclined wall 57 for the introduction of the chute. 85

58 represents the chute, which has its lower end removably fitted to an opening in the inclined wall 57 and there provided with a discharge-mouth 59, which projects into the generating-chamber. The discharge-mouth 59 is 90 guarded against the escape of gas by means of the fender 60, which projects inwardly beneath and on both sides of the discharge-mouth, so that the gas which is generated and which rises vertically must pass around 95 the discharge-mouth in ascending. The chute 58 is supported for the most part by its connection with the inclined wall 57; but it has its upper end fitted well between the diaphragm 46. It is, however, not attached to 100 diaphragm, and the latter, along with the trap 39, is lifted out by the removal of the carbid holding and delivering mechanism.

To provide for the ready removal of the parts when necessary, the head 40 is fitted 105 upon, but not attached to, the cylindrical wall 48 and may be lifted off at any time without difficulty, after which the chute 58 is readily disengaged by a slight movement toward the center and may then be lifted out. After removing the chute 58 the hood 54 is likewise 110 readily removable, and access is thus given to the bottom of the generator, which may be then thoroughly cleaned. For ordinary cleaning, however, I employ a sliding gate 61, (see 115 Fig. 1,) which is controlled by a lever 62.

63 represents an agitator which may be employed for stirring up the precipitate and drawing off the water, so as to remove it from the bottom of the generator. 120

64 represents a deflector of peculiar shape which serves the purpose of directing the carbid laterally from beneath the supply-chute. It is inclined from its ends toward the middle and likewise from the central line laterally. The object in so constructing the deflector 64 is to more effectively protect the supply-opening and at the same time to admit the agitator 63 beneath the deflector. 125

The chute 58 is preferably made with a collecting-chamber 65, having an outlet 66, in which will gather any gas which might escape back through the opening 59 and discharge said gas into the waste-chamber B, 130

from which it escapes through the discharge-outlet 67 and is delivered through the waste-pipe 20. (See Fig. 1.)

Water is kept in the generator at about the 5 level shown. Water may freely communicate between the generating-chamber C and the waste-chamber B through openings 68 at the base of the hood 54. (See Figs. 2 and 4.) These openings are protected by means of the 10 guard 56, so that gas cannot escape there-through.

Having thus described my invention, the following is what I claim as new therein and desire to secure by Letters Patent:

15 1. In an acetylene-gas generator, the combination of the generating-chamber, a waste-chamber and a carbid-chamber arranged in vertical series and each separated from the rest, and carbid carrying and delivering mechanism located in and inclosed by the carbid-chamber; substantially as and for the purposes set forth.

20 2. In an acetylene-machine, the combination of a generating-chamber, a waste-chamber, and a carbid-chamber communicating with the generating-chamber by a chute extending through the waste-chamber.

25 3. In an acetylene-machine, the combination of the generating-chamber, the waste-chamber above the generating-chamber, and the carbid-chamber above the waste-chamber communicating with the generating-chamber through a water-sealed chute, said chute having a gas-trap communicating with the waste-chamber.

30 4. In an acetylene-machine, the combination of the generating, waste, and carbid chambers arranged in vertical series, a chute communicating between the carbid and generating chambers, and a gas-trap in the chute communicating with the waste-chamber and water-sealed from the passage into the carbid-chamber.

35 5. In combination with an acetylene-gas generator, a carbid-chamber, horizontally-rotating mechanism for carrying and delivering charges of carbid located in said chamber, detachable carbid-holders forming part of such mechanism, and a door in the side wall 40 of said carbid-chamber through which the holders may be removed and replaced as they are successively brought opposite thereto by rotation of the carrier; substantially in the manner and for the purposes set forth.

45 6. In combination with an acetylene-gas generator, a closed carbid-chamber, a rotating mechanism for supporting the carbid, holders detachably mounted upon said carbid-holder and brought by the latter successively 50 into position for delivering their contents to the generator, and a restricted door in the carbid-chamber to which the removable holders are successively brought by rotation of the supporting mechanism after passing the 55 discharging position; substantially as and for the purposes set forth.

7. In combination with an acetylene-gas generator, the rotary supporting-spider having radially-slotted arms, and the carbid-holders detachably mounted upon said arms 70 by means of T-heads which fit in the slots, and a discharging-trip engaging the holders in a circumferential direction; substantially in the manner and for the purposes set forth.

8. In combination with an acetylene-gas 75 machine, dumping carbid-holders and an automatically-closing trap through which the holders dump; said trap being formed by the downwardly-projecting triangular walls 51 and the angularly-arranged doors automatically closing against the inclined edges of said walls; substantially as set forth.

9. In combination with an acetylene-gas generator, the head 40 resting upon the body 80 of the generator, the diaphragm 46 carrying the mechanism for controlling the discharge of the carbid, and suspended from said head and removable with it; substantially in the manner and for the purposes set forth.

10. In an acetylene-gas generator, the combination of the body of the generator, the removable head 40, the frame 42 suspended from the head by means of the rods 41, the shaft 6 having bearings in the head and in said frame, the carbid carrying and delivering 95 mechanism mounted on said shaft, the diaphragm 46 supported upon said frame, and the trap 39 mounted on the diaphragm and through which the carbid discharges; substantially as set forth.

100 11. In an acetylene-gas machine, the combination of a generating-chamber, a waste-chamber located above and separated from the generating-chamber, and a carbid-chamber located above and separated from the 105 waste-chamber; substantially as and for the purposes set forth.

110 12. In an acetylene-gas machine, the combination of the body of the generator, the tapered hood 54 located in and removable from the body of the generator and forming a generating-chamber therein, and a detachable chute for delivering carbid through the inclined wall of the hood; substantially as explained.

115 13. In combination with the body of the generator, the hood 54 located therein and providing a generating-chamber, and the guard 56 for preventing the escape of gas passed through the lower edge of the hood; substantially as and for the purposes set forth.

120 14. In combination with the body of the generator, having the ledge 55 projecting inwardly from its inner wall, the hood 54 having its lower edge resting upon the ledge 55, and the guard 56; substantially as and for the purposes set forth.

125 15. In an acetylene-gas generator, the combination of the removable hood 54 located therein and providing a generating-chamber, 130 and the chute 58 projecting through a side wall of the hood and delivering carbid there-

into; substantially as and for the purposes set forth.

16. In an acetylene-gas generator, the combination of the hood 54 inclined upwardly and laterally and providing the inclined wall 57, the chute 58 projecting downwardly in said generator and entering the inclined wall 57, and suitable means for delivering carbide into said chute; substantially as and for the purposes set forth.

17. In an acetylene-gas generator, the combination of the hood 54, the chute 58 delivering into said hood, and the deflector 64 inclined downwardly from its ends to the center

and from its middle line laterally; substantially as and for the purposes set forth.

18. In an acetylene-gas generator, the combination of the waste-chamber B, the hood 54 providing the generating-chamber C and having openings 68 at its base through which water may pass from one chamber to the other, and the guard 56 projecting upwardly within the base of the hood; substantially as set forth.

ADDISON V. SANFORD.
